UNITED STATES PATENT OFFICE

GEORGE H. EMERSON, OF ST. PAUL, MINNESOTA.

SPARK-EXTINGUISHER.

1,171,934.

Specification of Letters Patent. Patented Feb. 15, 1916.

Application filed April 17, 1915. Serial No. 22,156.

To all whom it may concern:

Be it known that I, GEORGE H. EMERSON, citizen of the United States, resident of St. Paul, county of Ramsey, State of Minnesota, have invented certain new and useful Improvements in Spark-Extinguishers, of which the following is a specification.

The object of my invention is to provide an attachment for the smoke box of a locomotive which will compel the burning embers and cinders discharged into the smoke box through the flues to follow a tortuous path through the smoke box and insure their being extinguished before entering the stack.

15 The invention consists generally in various constructions and combinations, all as hereinafter described and particularly pointed out in the claims.

In the accompanying drawings forming 20 part of this specification, Figure 1 is a vertical sectional view through a smoke box embodying my invention, Fig. 2 is a vertical sectional view in front of the exhaust nozzle on section line z—z, Fig. 3 is a sectional 25 view on the line x—x of Fig. 1.

In the drawings, 2 represents the forward portion of the boiler, having the usual flue sheet 3 and flues 4.

5 is the exhaust nozzle, communicating 30 with the engine cylinders and projecting up through the dead plate 6 in the usual way.

7 is a screen in the form of a double-ended cone, having its lower portion closed by the dead plate and arranged concentric with the 35 exhaust nozzle and communicating at its upper end with the stack 8. In the rear of this screen 7 I arrange a plate 9, disposed at an incline adjacent to the forward ends of the flues and having a backwardly turned 40 upper portion 10 seated upon a baffle plate that is supported at 11 on the flue sheet of the boiler. This plate 9 is provided with a series of corrugations 12, extending transversely of the smoke box, forming teeth 13

45 against which the burning embers and cinders are thrown and broken up and disintegrated, and directed downwardly toward the bottom of the smoke box. A similar corrugated plate 14 is adjustably mounted on the 50 forward end of the dead plate beneath the screen 7 and adjacent to the nozzle and operates as an apron to check the stream of burning cinders and effect a further breaking up of them, throwing them downwardly

toward the bottom of the smoke box. 55 Beneath this plate 14 is a plate 15, arranged in the lower forward portion of the smoke box and inclined upwardly and also having teeth formed thereon against which the cinders are thrown, there being a comparatively 60 narrow throat formed between this plate and the plate 14. In front of the smoke box a large toothed plate 16 is arranged vertically, extending entirely across the front wall and having its teeth positioned to engage the embers and cinders and crush and break them as they are thrown forward through the throat between the plates 14 and 15. A plate 16' is mounted within an opening in the plate 16 through which convenient 65 access may be had to the front of the smoke box. At the top of the smoke box is still another plate 17, corresponding substantially to the plate 15 but inclined upwardly and 70 backwardly, so that when the cinders come 75 in contact with it they will be arrested and thrown backwardly and downwardly against the wall of the screen 7, and by the successive engagement with these roughened or toothed plates they will be so thoroughly disintegrated that when they contact with the 80 screen 7 they may pass through it, the fire being wholly extinguished, or may drop down to the bottom of the smoke box. I am thus able to positively prevent the 85 discharge of burning embers or cinders from the locomotive stack. The corrugations 85 may be formed in various ways and the plates in which these corrugations are arranged may be varied in shape, according 90 to the desired location of the smoke box, and in various ways the details of construction may be modified and still be within the 90 scope of my invention.

I claim as my invention:

1. The combination, with a locomotive smoke box, an exhaust nozzle and a screen interposed between the nozzle and stack and a dead plate provided in the lower portion of said screen, of a roughened plate forming a forwardly and downwardly inclined extension of said dead plate, for the purpose 100 specified.

2. The combination, with a locomotive smoke box having an exhaust nozzle, a stack, a screen interposed between said nozzle and stack, and a dead plate in the lower portion of said screen, of plates having roughened 105

surfaces arranged upon each side of said dead plate, one of said roughened plates extending upwardly and backwardly from said dead plate toward the flue sheet of the 5 boiler and the other roughened plate extending forwardly and downwardly from the forward portion of said dead plate.

In witness whereof, I have hereunto set my hand this 12th day of April, 1915.

GEORGE H. EMERSON.
